(57) **CLAIM**

The ornamental design for a tarp holder as shown and described.

DESCRIPTION

FIG. 1 is a front view of a tarp holder showing my new design;

FIG. 2 is a rear view of the tarp holder;

FIG. 3 is a right side view of the tarp holder;

FIG. 4 is a left side view of the tarp holder;

FIG. 5 is a top view of the tarp holder;

FIG. 6 is a bottom view of the tarp holder;

FIG. 7 is a top front right side perspective view of the tarp holder; and,

FIG. 8 is a top front right side perspective view of the tarp holder in use.

The broken lines in the drawings depict portions of the tarp holder that form no part of the claimed design. The additional broken lines in FIG. 8 are for environmental purposes only and form no part of the claimed design. The unshaded surfaces shown between solid and broken lines in FIG. 4 form no part of the claimed design.
